UNITED STATES PATENT OFFICE.

THOMAS G. PLANT, OF BOSTON, MASSACHUSETTS, ASSIGNOR TO MANUFACTURERS MACHINE COMPANY, OF MONTCLAIR, NEW JERSEY, A CORPORATION OF NEW JERSEY.

WELT-MEASURING MEANS FOR SEWING-MACHINES.

No. 377,859.

Specification of Letters Patent.

Patented Jan. 28, 1908.

Application filed December 3, 1906. Serial No. 345,993.

To all whom it may concern:

Be it known that I, THOMAS G. PLANT, a citizen of the United States, residing at Boston, in the county of Suffolk and State of Massachusetts, have invented an Improvement in Welt-Measuring Means for Sewing-Machines, of which the following description, in connection with the accompanying drawings, is a specification, like letters on the drawings representing like parts.

This invention relates to sewing machines adapted to sew upon or in connection with a strip of fabric or other material fed to the machine as the work progresses, the general object of the invention being to provide means for controlling the strip in such manner as to present always the required length of strip at the proper point at the required time or times.

My invention is particularly adapted for use in connection with what are known as "welt sewing machines" or "welters" used extensively in the manufacture of boots and shoes in sewing the narrow strip of leather commonly known as the "welt" to the upper and insole of the boot or shoe, preparatory to the application thereto of the usual outsole. When so used, my invention is useful, among other things, in presenting at the required times the proper length of welt end to assist in the application thereof to the boot or shoe and also to guard against unnecessary waste of welt. While this is the principal use to which I now contemplate putting my invention and shall, therefore, disclose my invention in connection with an embodiment thereof for this particular purpose, it is to be understood, that my invention is not limited to this particular use nor to this embodiment thereof but includes any use in connection with any strip for any purpose to which it may be adapted.

My invention will be best understood from the following description of one embodiment thereof well adapted for boot and shoe work.

In the drawings: Figure 1 is a front elevation of a welt sewing machine, adapted for "welt" boots and shoes, said machine being equipped with a device illustrating one embodiment of my invention; Fig. 2 is a detail of the welt controlling device illustrated in Fig. 1, the parts being shown on an enlarged scale; Fig. 3 is a right hand elevation of the parts shown in Fig. 2, and Fig. 4 is a

corner view, somewhat similar to Fig. 2, showing the parts in different positions.

In the particular embodiment of my invention selected for illustration herein and shown in the drawings, referring first to Fig. 1, the machine to which my invention is shown applied, may be of any usual or desired type, the machine here shown being of the curved needle type generally used in weltting. In the machine shown, the curved awl is indicated at 19, the channel guide at 30, the looper is typified at 36, and the slide rest at 98, these and their concomitant parts being organized and operating in a manner well understood by those skilled in the art without further description herein.

Viewing the machine from the front, as in Fig. 1, at the left of the stitch forming devices is shown a welt cutting device 136, adapted to cut or sever the welt that has been applied to the shoe from the supply end thereof, in order that the shoe may be removed from the machine. In the present instance this cutting device is such as shown in a pending application No. 336,465 filed by me Sept. 26, 1906, it being sufficient here to mention that the said cutting device, is constructed not only to cut but to hold the supply end of the welt in position to present the welt to the shoe next operated upon, in order that it may receive the initial forward stroke of the needle without requiring the operative to hold said welt end between his fingers and the side of the shoe, as has been heretofore the custom. This welt severing or cutting device is here operated by a chain c , attached to the free end of a lever c' , fulcrumed at c'' , on the machine bed and operated by a treadle rod 142, from a suitable treadle 142 $\times$, conveniently positioned at the base of the column of the machine. The usual welt guide is typified at 129, it being provided with means for moving it toward and from the work in a manner customary in machines for this purpose. At the right of the machine, as shown in Fig. 1, one of the standards 2, thereof, is provided with an angularly positioned stud 300, upon which is loosely journaled a pulley or roller 301, over which the welt w is passed as it is led from the welt supply, wherever located, to the welt guide. This roller is flanged as shown that it may better guide the welt and prevent displacement thereof.

105

Above the roller 301, is an elbow lever 302, loosely fulcrumed upon a stud 303, and which may be called a measuring lever, the same being provided at its depending end 5 with a loosely mounted roller or pulley 304, adapted to rest upon the welt *w*. A spring 305, encircling the hub of said lever 302, bears at one end upon the support for the stationary roller 301, and at its opposite end overlies said lever 302, tending to press said last mentioned lever normally downward as indicated in Figs. 1 and 2, thereby to deflect the welt *w* in its line of travel between the stationary pulley 301 and the welt guide. 10 The extent to which said welt may be so deflected is limited by an adjustable stop shown as a screw 305^x, standing above said lever 302, supported in an ear 306 on the standard of the machine. The horizontal 15 end of the lever 302 is shown connected by a chain 307 with the free end of a lever 308, fulcrumed at 309 on the bed of the machine. This lever, intermediate its ends, is connected by a spring 310 with a drop rod 20 311, preferably adjustable as to its length at 312. This drop rod at its lower end is connected to one end of an arm 313 on a treadle shaft 314 carrying the treadle 315. This treadle overlies at a suitable point the treadle 25 315^x or a part thereof, in order that, in the machine shown, depression of said treadle 315 may, at some point in its movement, engage and cause sufficient depression of the treadle 315^x to operate the welt cutting 30 device. 35 Before operating the machine, the parts will stand in the positions indicated in Figs. 1 to 3, the welt being deflected as there shown and held at its end in the clamping device 40 next or forming a part of the welt cutting device 136. The operative now presents a shoe to the stitch forming mechanism and starts his machine which, in the course of its operation, attaches the said welt in usual 45 manner to the shoe. When the welt has been completely attached the operative stops the machine but he cannot remove the shoe without first severing the attached welt portion from the supply portion thereof leading 50 to it through the welt guide. To accomplish this, the operative now depresses the treadle 315, which causes the elbow lever 302 to be tipped into its position shown in Fig. 4, thereby slackening the welt between the stationary roller 301 and the welt guide and permitting the operative to carry the shoe to the 55 left a sufficient distance to engage the welt with the welt cutting device, which is operated to cut the welt by the continued depression of the treadle 315 carrying the welt cutting treadle 315^x before it. 60

When the elbow lever 302 is tipped into its position in Fig. 4 to slacken the welt and permit the latter to run in a straight line from 65 the stationary roller 301 to the welt guide,

the horizontal arm of said lever is brought down upon and is arrested by contact with the welt *w* at a point where it passes over the said stationary roller 301. The engaging surface of said horizontal arm (see Figs. 2 and 3) is provided with a suitable locking surface shown as a serrated shoe 316 the teeth of which face rearwardly and which serve to lock the welt against any further movement or travel in the direction of the welt guide or shoe. Thus, when the welt is slackened as described, the slack is wholly between the stationary roller and the shoe, the welt being locked as described where it passes over the roller so that the operative may withdraw the shoe and draw through the welt only to the extent permitted by the change in alinement of the welt from the deflected line of Figs. 1 and 2 to the straight line thereof illustrated in Fig. 4. In practice, this deflection is such as to furnish, when the welt is straightened, merely sufficient added length of welt to permit the shoe to be removed to a welt cutting position, whether the cutting is performed by a cutting device that is a part of the machine, 80 as herein, or otherwise, the welt being there locked so as to prevent waste by drawing through more than needed. In the depression of the welt measuring treadle 315 the elbow lever 302 is moved into its welt locking 85 position before the said treadle meets and moves the welt cutting treadle, and, further depression of the said measuring treadle 315 is thereafter permitted by the extension of the spring 310 for the purpose of depressing 90 the welt cutting treadle. 95

The supply end of the welt is retained as stated, held in the clamping part of the welt severing device, so that as soon as the welt is severed and the shoe freed the operative may 105 release the treadle 315 without danger of losing the welt end, which remains held in position for presentation to the needle when the next shoe is to be operated upon. When the said treadle 315 is released the elbow lever 110 302, under the action of its spring 305, resumes its normal position (Figs. 1 to 3 inclusive) and again deflects the welt between the stationary roller 301 and the welt guide, this deflection causing an additional supply of 115 welt to be drawn from the source to store the added length needed for withdrawal of the next completed shoe in the manner described. The tension of the spring 305 is sufficient to maintain the elbow lever in its position (Figs. 120 1 to 3 inclusive) during the operation of the machine, during which time the course of travel of the welt is in the deflected line indicated. Adjustment of the stop 305^x by varying the limit of the spring actuated deflecting movement of the elbow lever 302 125 varies correspondingly the deflection of the welt and the resultant length of welt or distance through which the shoe may be withdrawn for welt cutting. The lower end of 130

said elbow lever, adjacent the roller 304, is provided with a yoke 317, which embraces and prevents the welt bulging away from or becoming displaced relative to said roller 5 304.

The device described limits predeterminedly the withdrawal movement of the shoe before the welt is cut, and this may be so adjusted or regulated as to confine the withdrawal merely to what is sufficient to permit the welt to be cut. So, also, the device described furnishes a means for limiting predeterminedly the length of welt at the supply end of the cutting point which is 10 presented for engagement by the needle at the beginning of the operation of welting, thus avoiding a waste of welting in the severed end attached to and removed with the shoe and in the end that remains with the machine for presentation to the next shoe. By leaving the welt always of predetermined length where presented to the new shoe, there is a saving in the operative's time which is now required for pulling back the 15 welt needlessly drawn through the welt guide in the act of removing the shoe and for properly positioning and seizing it before beginning upon a new shoe.

My invention, obviously, is not limited to 20 the particular embodiment here shown for illustrative purposes, nor is it limited to the particular use herein disclosed.

In the claims the term "welt" is intended to include any strip of material and the term 25 "stitch forming mechanism" to include any means for attaching this strip in position or to the work.

1. In a welt attaching machine, a welt measuring device comprising stopping means 40 for limiting the withdrawal of the welt upon withdrawal of the work from the machine.

2. In a welt attaching machine, a welt measuring device comprising adjustable stopping means for limiting the withdrawal of 45 the welt upon withdrawal of the work from the machine.

3. The combination with welt end holding means of stopping means for limiting the travel of said welt in the direction of said 50 holding means.

4. The combination with welt cutting and welt end holding means of means for limiting

the travel of said welt in the direction of said holding means.

5. A welt-measuring device comprising 55 welt deflecting means, means for adjusting or regulating said welt-deflecting means so as to vary the deflection, means to sustain said welt to permit of such deflection, and stopping means to limit the forward travel 60 of the welt.

6. A welt measuring device comprising welt deflecting means, means to operate the deflecting means to permit the welt to be straightened, and a lock to hold the welt as 65 it is straightened.

7. The combination with welt severing means of welt measuring means, and common operating means for the two.

8. The combination of welt severing, welt 70 holding and welt measuring means of means common to and for operating the same.

9. The combination with a sewing machine and welt guiding means therefor of 75 welt measuring means for measuring the length of welt permitted to project beyond the stitch forming point.

10. The combination with a sewing machine of welt guiding means therefor, and welt measuring means comprising a welt 80 deflector and means to operate it.

11. A sewing machine comprising stitch forming mechanism, welt severing means at one side thereof, and welt measuring means at the opposite side thereof, and means to 85 operate the same.

12. The combination with a sewing machine of welt guiding means and welt measuring means comprising a welt deflector, means to operate it, and locking means to 90 lock the measured welt against change.

13. The combination with a sewing machine of welt guiding means and welt measuring means comprising means predeterminedly to change the line of travel of the welt 95 thereby to vary the length of welt permitted to be drawn to the work.

In testimony whereof, I have signed my name to this specification, in the presence of two subscribing witnesses.

THOMAS G. PLANT.
